Primary Examiner—Jennifer Rivard

(74) Attorney, Agent, or Firm—Sughrue Mion, PLLC

(57) **CLAIM**

The ornamental design for a protective cover for cable and piping material, as shown.

DESCRIPTION

FIG. 1 is a perspective view of a protective cover for cable and piping material showing my new design;

FIG. 2 is a front elevational view thereof; the rear elevational view being a mirror image;

FIG. 3 is a top plan view thereof;

FIG. 4 is a bottom plan view thereof;

FIG. 5 is a right side elevational view thereof; the left side elevational view being a mirror image;

FIG. 6 is a cross sectional view taken along lines 6—6 in FIG. 2.

FIG. 7 is a cross sectional view taken along lines 7—7 in FIG. 2.

FIG. 8 is a cross sectional view taken along lines 8—8 in FIG. 2; and,

FIG. 9 is a cross sectional view taken along lines 9—9 in FIG. 5.
